CLAIM

(22) Filed: **Dec. 13, 2016**

The ornamental design for a cyclonic strainer with helical brush combination, as shown and described.

(51) **LOC (10) Cl. 15-09**

DESCRIPTION

(52) **U.S. Cl.**

USPC **D15/138**

(58) **Field of Classification Search**

This application is related to U.S. application Ser. No. 12/874,876 filed on Sep. 2, 2010, which was filed in the name of the Applicant herein and issued into U.S. Pat. No. 8,978,753 on Mar. 17, 2015.

FIG. 1 is a perspective view of a cyclonic strainer with helical brush combination.

USPC D15/21, 28, 138, 139

FIG. 2 is a front view of the cyclonic strainer with helical brush combination of FIG. 1;

CPC E21B 43/38; E21B 43/127; F04B 47/00

FIG. 3 is a rear view of the cyclonic strainer with helical brush combination of FIG. 1;

See application file for complete search history.

FIG. 4 is a left side view of the cyclonic strainer with helical brush combination of FIG. 1;
